Inventor:

Wilhelm Ludowici

by Henry C. H. Hayes

UNITED STATES PATENT OFFICE.

WILHELM LUDOWICI, OF MUNICH, GERMANY.

TILED ROOF.

SPECIFICATION forming part of Letters Patent No. 772,363, dated October 18, 1904.

Application filed August 19, 1903. Serial No. 170,032. (No model.)

To all whom it may concern:

Be it known that I, WILHELM LUDOWICI, a subject of the King of Bavaria, residing at the city of Munich, Bavaria, German Empire, 5 have invented certain new and useful Improvements in Tiled Roofs; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to tiled roofs resembling those employed by the ancient Greeks in building temples.

My improved roofing, while being tempest-proof, does not require the employment of mortar. The joints are simple, but very effective.

My invention consists in the combination with tiles having stepped and recessed sides which when two tiles are laid together form small chambers or mortises, of ridge or covering tiles with lateral fillets, and tenons fitting into the said mortises.

My invention is shown in the accompanying drawings, in which—

Figure 1 is a plan, and Fig. 2 an under side view, of the flat tile. Fig. 3 is a section on the line *x x* of Fig. 1. Fig. 4 is a side elevation, and Fig. 5 a front elevation, of the tile. Fig. 6 is a section on the line *y y* of Fig. 2. Fig. 7 is a plan of the ridge or covering tile. Fig. 8 is an under side view of the same. Fig. 9 is a section on the line *w w* of Fig. 7. Fig. 10 is a section through two flat tiles with ridge-tile, taken on the line *v v* of Fig. 12, only the joining portions of the flat tiles being shown. Fig. 11 is a section through two flat tiles with ridge-tile, taken on the line *n n* of Fig. 12, portions of the flat tiles being broken away. Fig. 12 is a section through the ridge-tile on the line *s s* of Fig. 8, the coöperating flat tile being shown in elevation. Fig. 13 is a plan of a piece of finished roofing drawn to a reduced scale.

The tile consists of a flat slab *a*, having the sides inwardly stepped at *b*. At one end of the slab are the fillets or ribs *c d e*, and at the opposite end on the under side of the slab are the nib-fillets *f g h*. Below the ribs *c d e* a nib-fillet *i* is also provided. The fillets or steps *b* are recessed at *k k*, which recesses at each joint form with the like recesses of the adjacent tile small chambers.

The ridge-tile, Figs. 7, 8, and 9, consists of a front part *l*, which may be in the form of a rounded or pointed arch. The under side of this ridge-tile is stepped at *b'* to correspond with and cover the stepped portion *b* of the flat tiles *a*. The ridge-tile has a shoulder at *m* and a narrower projection or tongue *n*, and, furthermore, tenons *z z*, each adapted to engage in a chamber *k*, which thus constitutes a coöperating mortise.

Tiling is laid in the following manner: The flat tiles *a* are hung on the battens by means of the nib-fillet *i* in the ordinary manner and the fillets *f g h* inserted into the grooves between the fillets *c d e* of the adjacent tile. Between each two abutting tiles elevations or ridges *b b'*, stepped on either side, will thus be formed, and over these elevations the ridge-tiles *l* are laid, the tenons *z* of which will fit into the chambers *k*, which are formed on the junction-line of each two adjacent tiles *a*, as already explained.

Having thus described my invention, what I claim as new, and desire to secure by Letters Patent, is—

1. The combination with laterally-stepped tiles, of ridge-tiles having counter-steps engaging the steps of the aforesaid tiles.
2. The combination with flat, laterally stepped and recessed tiles, of ridge-tiles having counter-steps and tenons engaging the steps and recesses of the flat tiles.
3. A tile having stepped sides, transverse fillets at one end of the top face, nib-fillets on the opposite end and face, and a nib on the latter face at the end opposite the nib-fillets.
4. A roof-covering comprising a plurality of tiles each having inwardly-stepped and re-

cessed sides, transverse fillets at one end of their top faces, nib-fillets on the opposite end and face of each tile, and a nib on the latter face at the opposite end, in combination with ridge-tiles having steps adapted to engage the steps of the aforesaid tiles and tenons on the under face of each tile adapted to engage said recesses.

In testimony that I claim the foregoing as my invention I have signed my name in presence of two subscribing witnesses.

WILHELM LUDOWICI.
